UNITED STATES PATENT OFFICE.

THOMAS R. JENKINS, JR., OF BALTIMORE, MARYLAND, ASSIGNOR OF ONE-HALF TO
WALTER S. FINNELL, OF BALTIMORE, MARYLAND.

MACHINE FOR REMOVING WATER FROM FLOORS.

1,006,221.

Specification of Letters Patent.

Patented Oct. 17, 1911.

Application filed October 13, 1908. Serial No. 457,451.

To all whom it may concern:

Be it known that I, THOMAS R. JENKINS, Jr., a citizen of the United States, residing at Baltimore, in the State of Maryland, have invented certain new and useful Improvements in Machines for Removing Water from Floors, of which the following is a specification.

This invention relates to a machine for collecting and removing water from floors after the latter have been scrubbed or washed.

A machine embodying the features of the present invention is especially useful during the washing or scrubbing of floors of considerable area, such as in public buildings where the washing of the floor is a considerable task, and the object of the invention is to provide an improved construction of machine which may be rolled over the floor and remove the water deposited thereon during the washing or scrubbing operation.

The washing or scrubbing may be effected in any suitable manner, either by hand or machine, to loosen the dirt and to effect the scouring of the floor surface, but by means of the present invention the usual mopping and drying of the floor may be dispensed with as the improved machine will collect and raise the dirt and water from the floor and deposit it in a suitable receptacle as it is rolled over a floor surface.

The invention is illustrated in the accompanying drawings wherein—

Figure 1 is a side elevation of the machine embodying the invention. Fig. 2, is a top plan view thereof. Fig. 3, a front elevation of the same, and Fig. 4, is a vertical longitudinal section through the receiving receptacle and frame of the machine and also through the yielding collector plates.

Referring to the drawings, the numeral, 1, designates a bottom horizontal frame, preferably provided with a central opening, 2, for the purpose of reducing weight and also having vertical flanges, 3, at opposite sides. At the rear, the bottom frame is provided with rearwardly-projecting lugs or arms, 4, which serve as bearings for a horizontal shaft or axle, 5. Wheels, 6, are mounted on the outer ends of the shaft or axle and are preferably provided with tires, 7, of rubber or equivalent material.

A housing is preferably provided or top 55 of the bottom frame and in the present in-

stance comprises the vertical side plates, 8, and vertical front plate, 9. These plates have their lower ends secured by screws, 10, to the bottom frame and their upper ends similarly secured to an upper frame, 11. 60

A bracket, 12, is secured to the front plate, 9, adjacent one vertical edge thereof and said bracket carries a bearing, 13, through which a horizontal shaft, 14, extends. The outer end of this shaft carries a sprocket 65 wheel, 15, while the inner end thereof is provided with a crank, 16, having a wrist-pin.

A sprocket chain, 18, passes around the wheel, 15, and also around a sprocket wheel, 19, on the shaft or axle, 5, from which power 70 is derived when the machine is rolled over the floor.

Brackets, 20, and, 21, are one above the other secured to the front vertical plate, 9, of the housing and the tubular cylinder of a 75 pump, 22, extends vertically through and is sustained by said brackets. The lower end of the pump is provided with a sleeve, 23, of rubber which terminates adjacent the floor. 80

Above the bracket, 20, the pump is provided with a nozzle, 24, which projects through the front wall, 9, and opens or discharges downwardly into a suitable receptacle, 25, that is seated on the bottom frame 85 and also on the arms or lugs, 4. This receptacle is provided with a cover wall, 26, at its rear and a similar cover wall, 27, at its front so as to prevent splashing out of contents during the operation of rolling the machine back and forth over the floor. A suitable bail, 28, having a handle is attached to the receptacle for convenience in handling the latter. 90

The particular construction of the pump 95 is immaterial but in practice I provide a pump of the double action character having a stem, 29, to which a laterally-projecting arm, 30, is attached and I connect said stem arm with the wrist pin, 17, of the 100 crank by means of a rod, 31, so that as the crank turns the rod will be reciprocated vertically and a vertical reciprocation of the pump stem thereby produced.

A suitable bracket, 32, is mounted on top 105 of the housing and extends upwardly therefrom so as to serve as a guide for the upper end of the pump-stem.

The bracket, 21, is provided with an extension, 33, which pivotally sustains a stem, 110

34, having a yoke, 35, at its lower end in which is mounted a roller, 36. The upper end of the stem is provided with a cap, 37, that carries downwardly-projecting fingers, 38. These fingers have position at opposite sides of the bracket extension, 33, and limit the turning movement of the stem by contacting with the sides of the projection. A spiral spring, 39, is coiled about the stem 10 and has position between the upper side of the yoke and the lower side of the bracket-projections so as to provide a support for the pump end of the machine. This support is important in that without it during 15 the forward movement of the machine, the frictional contact of the flexible strip, 42, with the floor would cause the machine to vibrate vertically and in doing so would allow water and dirt to pass beneath the 20 strips and leave the floor in a streaked condition. By means of the support the pressure on the strips is merely sufficient to keep the latter in contact with the floor.

In order to increase the efficiency of the 25 machine and the area of its action, I provide means for collecting the water and delivering it to a point adjacent the pump where it may be readily elevated as will now be described.

30 The vertical flanges, 3, at opposite sides of the machine carry forwardly-projecting arms, 40, which sustain a horizontal plate, 41. Midway between its ends this plate has position immediately behind the pump 35 and from said point the two ends thereof extend forwardly in an oblique direction so that the plate has somewhat the form of a V. One or more sheets, or strips, 42, of flexible material are placed vertically 40 against the front side of the plate, 41, so that the lower edge thereof may rest upon or contact with the floor. In practice, this flexible material has the form of strips of 45 rubber of sufficient stiffness to act as scrapers, and a reinforce plate, 43, is placed on the outer side of the strip or strips to clamp

them against the plate, 41, by means of screws, 44.

An operating handle comprising side bars, 45, and a horizontal crossbar, 46, is 50 pivotally connected to the bottom frame, 1, and by means of which the machine may be conveniently pushed along the floor or surface to be operated upon.

In the operation, the machine is pushed 55 over the floor while the scraper strips, 42, contact with the floor surface and collect the water and dirt and direct it toward a central point beneath the pump. The revolution of the wheels, 6, drives the shaft or 60 axle, 5, and the sprocket wheel, 19, while the chain 18, drives sprocket, 15, shaft, 14, and crank, 16. The rod, 31, operating between the crank and pump-stem, 29, converts the rotary motion of the crank into a 65 reciprocating motion at the pump. As the water and small particles of dirt are accumulated beneath the pump the latter will suck the same up and discharge it through the nozzle into the receptacle, 25. 70

Having thus described my invention what I claim and desire to secure by Letters Patent is,—

In a machine of the character described the combination with a horizontal frame, of 75 a pair of wheels at the rear end of the frame; a yieldingly-sustained wheel at the front of the said frame; a pump casing depending below the frame at the rear of the yieldingly-sustained front wheel; a flexible 80 scraper in the rear of the pump casing and a handle attached to the machine and projecting rearwardly of the pair of rear wheels whereby the machine may be rocked on the rear wheels to raise the scraper from 85 the floor.

In testimony whereof I affix my signature in presence of two witnesses.

THOMAS R. JENKINS, JR.
